UNITED STATES PATENT OFFICE.

HUBERT F. KRANTZ, OF BROOKLYN, NEW YORK, ASSIGNEE TO KRANTZ MANUFACTURING COMPANY, INC., OF BROOKLYN, NEW YORK, A CORPORATION OF NEW YORK.

SAFETY CUT-OUT.

1,398,489.

Specification of Letters Patent.

Patented Dec. 6, 1921.

Application filed April 3, 1916. Serial No. 99,860.

To all whom it may concern:

Be it known that I, HUBERT F. KRANTZ, a citizen of the United States, and residing at Brooklyn in the county of Kings and State of New York, have invented a new and Improved Safety Cut-Out, of which the following specification is a full disclosure.

This invention relates to a switch mechanism for controlling electrical circuits and it proposes the provision of features, one or more of which may be utilized in achieving one or more of the following objects.

A primary object is to create a switch organization so incased or inclosed that it cannot be operated except with a special key and which can only be accessible when all current carrying parts have been first rendered "dead."

Another object is to provide a switch so incased that, when in its closed circuit position, it will also lock the door against opening.

Another object is to provide a switch mechanism adapted to operate automatically by a change in the load of the circuit, in conjunction with a special key arrangement whereby an unauthorized person may not operate the same; together with means affording the freest possible inspection of all of the working parts while at the same time insuring that they will be "dead" during such periods of inspection or repair.

Other objects will be in part obvious from the annexed drawings and in part indicated in connection therewith by the following analysis of this invention.

This invention accordingly consists in the features of construction, combination of parts and in the unique relations of the members and the relative proportioning and disposition thereof; all as more completely outlined herein.

To enable others skilled in the art so fully to comprehend the underlying features thereof that they may embody the same by the numerous modifications in structure and relation contemplated by this invention, drawings depicting a preferred form have been annexed as a part of this disclosure, and in such drawings, like characters of reference denote corresponding parts throughout all the views; of which:

Figure 1 is a sectional side elevation of this mechanism showing parts in full

lines in the door-locked close-circuit position of the switch. Fig. 2 is a top view of this arrangement with the door swung into its vertical open position. Fig. 3 is an inverted section with the base of the box removed and looking upwardly as indicated by the arrows marked 3 in Fig. 1.

The form in which the various elements have been illustrated will suffice to typify the modifications which they may assume. Thus, A indicates a structure in the nature of a housing or casing adapted normally to obstruct access to the operating elements. Here, this casing assumes the form of a box formed of a base 1, the end walls 2 and 3, the side walls 4 and 5 and the stationary top 6. This top is provided with a cut-away portion providing an opening 7 for the purpose of affording access to the parts to enable them to be replaced or inspected. This opening is normally closed by means of a door or cover B arranged to be readily displaced from its closing position as being hinged at 8 to the stationary top. A portion of this door as indicated by B' serves as an apron or shield which lies out of the way when the door is closed and enables the switch blade to make contact with the live main-line terminal C; and yet which takes an obstructing position, operating as a barrier to prevent the hand from contacting with said terminal when the door is opened. This is understood by referring to Fig. 1, showing in dotted lines the successive positions taken by the apron. The apron is provided with a slot 9 (see Fig. 3) through which the terminal C normally protrudes. This terminal is in turn connected in any suitable manner with a main-line conductor 10, as by means of the strip 11, which runs closely underneath the stationary top 6.

The switch device is preferably so mounted that it will be shifted into a more accessible position whenever the door is opened, and a convenient manner of doing this is to mount the same directly on said door. Thus, this switch device consists of a frame D, positioned on the cover B by means of studs 12, so that the swinging switch blade or brush may make contact with the main-line terminal C on the one hand and with the branch-line terminal E on the other hand. This brush F is preferably pivoted as by being clamped to a rocker 13 which swings about a vertical pivot 14. The blade F is of lami-

nated construction, being formed of successive layers of copper sheets, clamped together near their middle by means of rivets 15 and thereby secured to the rocker 13. A 5 spring 16, tends constantly to throw the switch into its neutral position as indicated in dotted lines in Fig. 3 and this movement may be prevented by means of a toggle formed of links G and H. Link H swings 10 about the fixed pivot 17 and is connected by means of the moving pivot 18 to the floating link G which in turn is connected at 19 to the rocker 13. The pin 20 serves to hold the toggle slightly over its dead center position 15 when it is erected and thus flex the resilient brush against its terminals. By reason of the resiliency of this brush no difficulty arises when the switch device is displaced bodily since this construction precludes the 20 necessity of accurate alinement of parts. The toggle may be broken or erected by means of a special key 29 adapted to be inserted through the keyhole 22 from the exterior of the door B. In breaking the toggle the swinging extremity of the key will 25 impact the shoulder 21 of the link G thereby swinging it anti-clockwise over its dead center, and this will then allow the spring 16 to exert itself and throw the toggle into the 30 dotted line position indicated by Fig. 3; thereby moving the switch into its open circuit position. On the other hand, with the parts in this position, the free end of the key may swing against the shoulder 23 by 35 a reverse movement and restore the parts to their initial erected position. The angular relation of the shoulders 21 and 23 to each other provide spaced legs, as of a bell-crank upon the link H, so that the key is free to 40 play within the space between the legs and is operable to swing the bell-crank in either direction according as the key is turned against one leg or the other.

It will be observed that when the brush 45 F is in the closed circuit position, the door cannot be opened, because the end of the brush adjacent the terminal E lies underneath the lip 24 of the stationary cover which would obstruct its upward rise. 50 When in open circuit position, however, the brush clears said lip and the door may readily be opened.

This invention furthermore proposes an arrangement for automatically operating a 55 switch device under special conditions, as for example, when a load varies from the normal. Thus, K indicates a solenoid formed of a few turns of heavy copper wire arranged in series with the branch-line circuit and the 60 terminal E. Should the current become excessive this solenoid will pull the plunger L to the right and this plunger is in turn pivoted to a lever M pivoted at 25 to the frame 26 so that the upper end 27 of the lever may 65 move against the extension 28 of the link H

and swing it about the pivot 17 so as to break the toggle. The adjacent ends of the parts 27 and 28 are shown beveled to prevent the lever 27 from catching under the part 28 and interfere with the closing of the door.

70

Without further analysis, the foregoing will so fully reveal the gist of this invention that others can by applying current knowledge readily adapt it for various applications without omitting certain features that, 75 from the standpoint of the prior art, fairly constitute essential characteristics of the generic or specific aspects of this invention, and therefore such adaptations should and are intended to be comprehended within the 80 meaning and range of equivalency of the following claims.

75

Having thus revealed this invention, I claim as new and desire to secure the following combinations of elements, or equivalents thereof, by Letters Patent of the 85 United States:

85

1. A switch mechanism combining a housing having an opening thereinto, a door for said opening hinged to swing into open and closed positions, a switch mechanism arranged within the housing, said switch mechanism including a switch blade pivotally supported by the door upon an axis 90 extending transverse of the axis of the door hinge, and means to swing the switch blade into and out of a position in which the switch blade constitutes retaining means for the door.

90

2. A switch mechanism combining a housing having an opening thereinto, a door for said opening hinged to swing into open and closed positions, a switch mechanism arranged within the housing, said switch mechanism including a switch blade pivotally supported by the door upon an axis extending transverse of the axis of the door hinge, a contact carried by the housing beyond the margin of the door, means to swing the switch blade into and out of position 100 projecting beyond the margin of the door and into engagement with said contact, thus to directly constitute the switch blade as a retaining means for the door when the switch blade is in engagement with said 110 contact.

100

3. In a switch mechanism comprising a housing having a displaceable cover, a switch device within the housing accessible when said cover is displaced, said switch device 120 being operable into "on" and "off" positions, and means whereby the cover may not be displaced while the switch device is "on," the combination therewith of a key, and means adapted to be controlled thereby for operating said switch device into its "on" and "off" positions.

120

4. In a switch mechanism comprising a housing having a displaceable cover, a switch device within the housing ac- 130

130

- cessible when said cover is displaced, said switch device being operable into "on" and "off" positions, and means whereby the cover may not be displaced while 5 the switch device is "on," the combination therewith of key controlled operating means carried by said cover for operating said switch device into its "on" and "off" positions, a key, and the cover having 10 an aperture therethrough for the insertion of the key to operate said operating means.
5. A switching device comprising a housing having a cover provided with an opening, a door for said opening hinged to 15 swing into open and closed positions, a switch blade within the housing having a part movable into engagement with the cover and serving to retain the door closed, a toggle also within the housing operable into 20 "made" and "broken" positions and adapted, when in "made" position, to lock the switch blade in retaining position, and means to operate the toggle.
6. A switching device comprising a housing 25 having a cover provided with an opening, a door for said opening hinged to swing into open and closed positions, a switch blade within the housing and having a part movable into engagement with the cover and 30 serving to retain the door closed, and a part movable with the door and operable to lock the switch blade in its retaining position.
7. A switching device comprising a housing having a cover provided with an opening, a door for said opening hinged to swing 35 into open and closed positions, a switch blade carried by, and movable with, the door within the housing and having a part that is movable into engagement with the cover and 40 serving to retain the door closed, and means for locking the switch blade in its retaining position.
8. A switching device comprising a housing having an opening therein, a door for 45 said opening hinged to swing into open and closed positions, a switch blade within the housing, the door being arranged to swing upon a relatively vertical axis, the switch blade being so pivotally mounted upon the 50 door on a horizontal axis as to swing in a plane substantially parallel to the plane of the inner surface of the door, the switch blade having a part that, in one position of the switch blade, co-operates with a portion 55 of the housing to retain the door closed, and means to lock the switch blade in said last mentioned position.
9. A switching device comprising a pair 60 of separate contact members, a movable support pivoted for rotary movement into operative and inoperative positions, a switch blade member pivoted to the support for rotary movement about an axis disposed sub-
- stantially at right angles to the axis of rotation of the support and adapted, when the support is in operative position, to be rotated into and out of engagement with the said contact members, and means for preventing movement of the support out of operative position while the blade member is in engagement with the contact members. 65
10. A switching device comprising a pair of separate contact members, a movable support pivoted for rotary movement into operative and inoperative positions, a switch 70 blade member pivoted to the support for rotary movement about an axis disposed substantially normal to the axis of rotation of the support and adapted, when the support is in operative position, to be rotated into 75 and out of engagement with the said contact members, means for preventing movement of the support out of operative position while the blade member is in engagement with the contact members, and means for holding the 80 blade member in engagement with the contact members. 85
11. A switching device comprising a pair of separate contact members, a movable support pivoted for rotary movement into 90 operative and inoperative positions, a switch blade member pivoted to the support for rotary movement about an axis disposed substantially normal to the axis of rotation of the support and adapted, when the support is in operative position, to be rotated into 95 and out of engagement with the said contact members, means for normally holding the blade member out of engagement with the contact member, means including a toggle 100 for operating the blade member into and out of engagement with the contact member and for holding the blade member in engagement with the contact members, and means for preventing movement of the support out 105 of operative position while the blade member is in engagement with the contact members.
12. A switching device comprising a housing having a cover provided with an opening therein, a door for said opening hinged to swing into open and closed positions, a switch blade located within the housing and carried by the said door and having a part 110 that is movable into and out of position beneath the cover to retain the door closed and means carried by the door for moving the switch blade and for locking the switch blade in its retaining position. 115

In witness whereof, I hereunto subscribe 120 my name, as attested by the two subscribing witnesses.

HUBERT F. KRANTZ.
